O. H. KOPP

SELECTIVE SWITCH

Filed Sept. 9, 1920

UNITED STATES PATENT OFFICE.

OTTMAR H. KOPP, OF BROOKLYN, NEW YORK, ASSIGNOR TO WESTERN ELECTRIC COMPANY, INCORPORATED, OF NEW YORK, N. Y., A CORPORATION OF NEW YORK.

SELECTIVE SWITCH.

Application filed September 9, 1920. Serial No. 409,130.

To all whom it may concern:

Be it known that I, OTTMAR H. KOPP, a citizen of the United States, residing at Brooklyn, in the county of Kings, State of New York, have invented certain new and useful Improvements in Selective Switches, of which the following is a full, clear, concise and exact description.

This invention relates to selective switches and particularly to switches of the types employed in automatic and semi-automatic telephone exchange systems.

Selectively operated switches are used for a variety of purposes in telephone systems, arranged for the extension of talking connections by machine switching apparatus. They are used to build up a circuit between subscribers' lines over which conversation may take place; to register designations, such as the identifying number of a calling or a called line; to select message registers and sources of ringing current for party lines and to accomplish other desired ends. When employed for the establishment of conversation circuits or for the registration of identifying designations, the operation of these switches is generally caused by current impulses resulting either directly or indirectly from some act of a subscriber or an operator.

In connection, especially, with switches of the step-by-step character, the selective movements of the switch are determined by series of impulses transmitted by means of manually operated sending devices. If the number of impulses in each series correctly represents the corresponding number or character of the designation concerned, the switches are accurately positioned. In practice, however, an improper manipulation of the controlling mechanism may cause the transmission of impulses which do not truly represent the designation desired and the switches are consequently incorrectly set. This difficulty is frequently encountered due to the subscriber disturbing his switch hook after the call is initiated and before he actuates the sender to transmit the first series of impulses. The result is that the accidental impulses will be added to the following series and the switch concerned takes an inaccurate setting.

With the foregoing possibility in mind the object of this invention is to eliminate

the detrimental effect of accidental impulses on the operation of selective switches.

A feature of the invention is the provision, in an arrangement where a selective switch is moved from position to position by current impulses, of means whereby, if a particular number of impulses are sent to move the switch to its corresponding position, a following series of impulses are effective to continue the movement of said switch to a position corresponding to the number of impulses contained in said series.

Another feature relates to means whereby, if the switch is correspondingly positioned by a particular number of preliminary impulses, a number of impulses of a following series equal to the number of said preliminary impulses will be rendered ineffective to move said switch, while the remaining impulses of said series cause the movement of the switch through a corresponding number of positions.

These and other features contemplated by the present invention will become more apparent from a consideration of the following description.

In the drawing, a diagrammatic illustration is given of a portion of an automatic telephone system embodying the features of the present invention. It will be understood, of course, that the invention in its broadest scope is applicable to any type of multi-position selective switch operated in response to transmitted impulses. In the embodiment taken for this illustration, however, it is shown as applied to a rotary step-by-step switch employed for registration purposes.

Referring particularly to the drawing, a subscriber's telephone line 100 is shown terminating in the brushes 102 and 103 of an individual line switch. The individual line switch has access to trunks leading to district selector switches, one of which is schematically illustrated by means of brushes 134 and 135 and a few other elements. The individual switch and the district selector switch may be of the type suitable for use in the well-known power drive panel type switching systems and are of the same general character as the corresponding switches shown in detail in the patent to Stearn and Scudder, No. 1,395,977, issued November 1, 1921. In the lower part of

the figure, there is illustrated a portion of a register sender upon which the designations of wanted lines are registered and which operates in accordance with the record 5 received to control the selective movements of the switches to establish the connection. The sender mechanism may likewise be of the same general nature as that shown and described in detail in the above-mentioned 10 Patent No. 1,395,977, issued November 1, 1921.

Each register of the sender, upon which a designation is recorded, is a step-by-step single motion rotary switch. Three of these 15 registers, 140, 160 and 180 are shown. The register 140 is provided with four circular banks of terminals and four brushes 141, 142, 143 and 144 cooperating with their respective banks. The register 160 is shown 20 with three banks of terminals with which the brushes 161, 162 and 163 cooperate. Register 180 also has three banks of terminals and three corresponding brushes 181, 182 and 183. The register switches 140, 160 and 25 180 are equipped with magnets 145, 164 and 184 respectively, which serve to advance the brushes in a step-by-step movement over the terminals.

The character 120 designates a control 30 switch, the function of which is to associate the impulse circuit successively with the several register switches. The control switch comprises four banks of terminals and four brushes 121, 122, 123 and 124. Magnet 125 35 operates to move these brushes step-by-step over their cooperating terminals.

A brief explanation having been given of the system to which the invention is applied a detailed description will now be made of 40 its operation.

Assume that the subscriber at substation 100 desires to obtain a telephone connection with another subscriber's line in the exchange. He initiates the call in the usual 45 manner by removing the receiver from the switch hook. The individual line switch brushes 102, 103 are thereupon driven to a set of terminals 104, 105 representing an idle district selector switch. When the district selector switch is seized, the sequence 50 switch 110, which controls the same, is advanced to a certain position in the manner fully explained in the above-mentioned Patent No. 1,395,977 issued November 1, 1921. 55 In this position, the lower contacts 106 and 107 of sequence switch 110 are closed and the calling subscriber's line is included in series with the windings of the impulse relay 108. Relay 108 becomes energized and closes a 60 circuit at its armature and front contact for the slow-to-release relay 109. Relay 109, in turn, closes a circuit for relay 111. Relay 111 completes a circuit from battery, through the winding of relay 116, normal 65 position terminal 136 of control switch 120,

brush 121, contact and right hand armature of relay 111 to ground. Relay 116 becomes energized and attracts its armature.

The calling subscriber now manipulates the impulse sender 101 to transmit a series of impulses corresponding to the first digit of the desired designation. The opening of the line circuit on the first impulse causes relay 108 to be deenergized. Relay 108 closes a circuit from ground, through its 70 armature and back contact, left hand armature and contact of relay 111, conductor 117, brush 123 of control switch 120, terminal 129, armature and back contact of relay 113, winding of stepping magnet 145 of the first 75 register switch 140, conductor 119, winding of slow-to-release relay 112 to battery and ground. Relay 112 and magnet 145 become energized in this circuit. When the line is closed at the termination of the first impulse, relay 108 attracts its armature and opens the above-traced circuit. The magnet 145 becomes deenergized and advances the brushes 141, 142, 143 and 144 from their 80 normal position to their first position terminals. For each succeeding impulse in the first series, relay 108 retracts and attracts its armature and magnet 145 is operated to 85 advance the brushes of switch 140 one position. Relays 109 and 112 being slow-to-release maintain their armatures attracted during the brief interruptions of their operating circuits at the armature and contacts of relay 108.

As will later be explained the first digit 100 of wanted designations is always greater than 1. Consequently, the first series contains more than one impulse and the brushes of switch 140 are advanced beyond their first position terminals. After a sufficient 105 interval following the closure of the line circuit at the termination of the last impulse, the slow-to-release relay 112 becomes deenergized and a circuit is completed from ground, through the right hand armature 110 and contact of said relay, winding of relay 114, brush 183 of switch 180, terminal 185, brush 163 of switch 160, terminal 165, brush 144 of switch 140 thence over the particular terminal engaged by the brush 144, contact 115 and armature and winding of magnet 145, conductor 119, winding of relay 112 to battery and ground. Relay 114 energizes in this circuit, but due to its high resistance sufficient current does not flow to operate 120 either the stepping magnet 145 or the relay 112. Relay 114 completes a circuit from ground through its armature and contact, normal position terminal 126, brush 122, left hand armature and contact of relay 112, contact 125 and armature and winding of stepping magnet 125 to battery and ground. Magnet 125 becomes energized, attracts its armature, opens its own circuit and again deenergizes. The deenergization of magnet 130

125 causes the advance of the brushes of the control switch 120 to their first position terminals. As brush 122 disengages terminal 126, the circuit of stepping magnet 125 is opened and consequently the control switch 120 stops in its first position. The movement of brush 121 from its normal position terminal 136 opens the circuit of relay 116 and this relay becomes deenergized.

10 The calling subscriber proceeds to manipulate the sender 101 to transmit the second series of impulses according to the second digit. When the impulse relay 108 deenergizes on the first interruption of the line circuit, a circuit is established from ground, through its armature and back contact, left hand armature and contact of relay 111, conductor 117, brush 123, terminal 130, winding of stepping magnet 164 of switch 160, conductor 119, winding of relay 112 to battery and ground. Relay 112 and magnet 164 become energized. At the end of the first impulse, relay 108 attracts its armature and magnet 164 deenergizes and advances brushes 161, 162 and 163 one position. In a similar manner, the remaining impulses of the series cause the successive advance of the brushes of switch 160. When the last impulse has been received, relay 108 maintains its armature attracted and relay 112 deenergizes after an interval. A circuit is now completed from ground, through the right hand armature and back contact of relay 112, winding of relay 114, brush 183, terminal 185, brush 163 and the particular terminal on which said brush is standing, contact and armature and winding of magnet 164, conductor 119, winding of relay 112 to battery and ground. Relay 114 becomes energized while magnet 164 and relay 112 remain inactive. The attraction of the armature of relay 114, however, is without effect since brush 122 of switch 120 is no longer in engagement with terminal 126. Relay 112 also closes a circuit from battery, through the winding and armature and contact of magnet 125, contact and left hand armature of relay 112, brush 122, terminal 127, conductor 190, brush 162 and the particular terminal on which said brush is standing to ground. Magnet 125 interrupts its own circuit and advances the brushes of the control switch to their second position terminals. Brush 122 in disengaging terminal 127 opens the above-traced circuit for magnet 125.

The calling subscriber operates the impulse sender 101 to send the third series of impulses and relay 108 retracts and attracts its armature for each interruption of the line. For each deenergization of relay 108, a circuit is closed from ground, through the armature and back contact of said relay, left hand armature and contact of relay 111, conductor 117, brush 123, terminal 131, wind-

ing of magnet 184, conductor 119, winding of relay 112 to battery and ground. Relay 184 operates to advance the brushes 181, 182 and 183 in a step-by-step motion over their terminal banks. At the end of this series of impulses, relay 112 releases its armatures and a circuit is completed from battery, through the winding and armature and contact of magnet 125, contact and left hand armature of relay 112, brush 122, terminal 128, brush 182 and the particular terminal on which said brush is standing to ground. Magnet 125 operates in this circuit to advance the brushes of the control switch to their third position terminals. Brush 122 on disengaging terminal 128 opens the operating circuit of magnet 125. Relay 112, at its right hand armature also closes a circuit, as has been explained, in series with itself and the windings of magnet 184 and relay 114. The energization of relay 114 is without effect and relay 112 and magnet 184 remain inactive due to the high resistance in series with their windings. In the manner above described, the calling subscriber may continue to transmit series of impulses to set as many succeeding register switches as the capacity of the system necessitates. The impulse circuit controlled at the armature and back contact of relay 108 is successively extended to the stepping magnets of the register switches, through the brush 123 of the control switch 120. The control switch may be advanced from position to position by circuits closed as described through the brush 122.

When the complete designation has been registered, a sender sequence switch 150 is started in operation to associate the registers in succession with a controlling mechanism, such as a set of counting relays. The banks of terminals over which the brushes 141, 161 and 181 move, may be wired in any suitable manner to the counting relays whereby the particular positions assumed by the register switches determine the movement of the selective switches in establishing the connection. After all the controlling functions have been completed by the sender, a contact 118, which may be operated by the sender sequence switch 150, is closed for the purpose of restoring the register switches to normal. It is not considered essential to illustrate and describe the complex circuit arrangement of the sender inasmuch as the present invention is concerned more particularly with the setting of the register switches.

The closure of contact 118 completes a circuit from battery, through the winding of relay 112, conductor 119, through the winding and armature and contact of magnet 184, brush 183, contact 118, to ground. Magnet 184 interrupts its own circuit and advances the brushes of switch 180 to their normal positions. When the brush 183

reaches normal, the circuit of magnet 184 is opened and a circuit is now completed by way of conductor 119, winding, armature and contact of magnet 164, brush 163, terminal 185, brush 183, contact 118 to ground. Magnet 164 restores the brushes of switch 160. Brush 163 on reaching its normal position opens the circuit of magnet 164 and closes a circuit by way of conductor 119, 70 winding and armature and contact of magnet 145, brush 144, terminal 165, brush 163, terminal 185, brush 183, contact 118 to ground. Magnet 145 likewise restores the brushes of switch 140 to their normal positions. 75

With the registers all restored, a circuit is closed from battery, through the winding and armature and contact of magnet 125, conductor 191, brush 124, said brush being 80 in engagement at this time with one of the terminals multiplied to conductor 191, terminal 147, brush 144, terminal 165, brush 163, terminal 185, brush 183, contact 118 to ground. Magnet 125 interrupts its circuit 85 to advance the brushes of the control switch 120 to their normal positions. 90

Thus far only the regular operation of the system has been considered. The calling subscriber has initiated the call and correctly manipulated the apparatus at his 95 disposal for causing the setting of the register switches in the exchange. A consideration will next be given the arrangement provided by this invention for obviating the detrimental effect of accidental preliminary impulses. 100

It frequently occurs that the subscriber inadvertently disturbs his switch hook after the call has been initiated and prior to the 105 transmission of the first series of impulses. A momentary actuation of the switch hook opens the line circuit and causes the deenergization and reenergization of relay 108. Consequently, a single impulse is transmitted 110 over brush 123, terminal 129, armature and back contact of relay 113, winding of magnet 145, conductor 119, winding of relay 112 to battery and ground. Magnet 145 steps the brushes of the register switch 140 to their first positions. At the end of the necessary interval, following the transmission of the accidental impulse, relay 112 deenergizes. A circuit is now closed from ground, through the right hand armature and contact of relay 112, brush 142, terminal 146, left hand winding of relay 113 to battery and ground. Relay 113 becomes energized in this circuit. It will be noted that the circuit hereinbefore traced for energizing relay 114, at the end of a series of impulses now extends from ground, through the right hand armature and contact of relay 112, winding of relay 114, brush 183, terminal 185, brush 163, terminal 165, brush 144, terminal 148 to the armature of relay 125

116. The relay 116, however, is energized and its armature is attracted to maintain the circuit of relay 114 open. Therefore the control switch 120 does not advance from its normal position in response to the deenergization of relay 112 following the preliminary impulse. 70

When the calling subscriber operates his sender 101 for the first digit, relay 108 responds to each impulse of the series. On the 75 first deenergization of relay 108, a circuit is completed from ground, through the armature and back contact of said relay, left hand armature and back contact of relay 111, conductor 117, brush 123, terminal 129, armature and front contact and right hand winding of relay 113, conductor 119 winding of relay 112 to battery and ground. Relay 112 becomes energized and opens the circuit through the left hand winding of relay 113. Relay 113, however, remains operated by means of the circuit, through its right hand winding and the winding of relay 112. At the end of the first impulse, relay 108 attracts its armature and opens the circuit through the right hand winding of relay 113 and the winding of relay 112. Relay 112 by reason of its slow-to-release character maintains its armatures attracted while relay 113 becomes deenergized. Hence, 85 the first impulse of the series, following the preliminary impulse, does not succeed in reaching the stepping magnet 145 and therefore the register switch 140 remains in its first position. The relay 113 now being deenergized each of the following impulses of the series are directed to the magnet 145 and switch 140 is driven forward from position to position in response to each of such impulses. From this point on the operation involved in the setting of the succeeding switches is identical with that already given. 90

It will be apparent that by reserving the first two or more positions of switch 140 for that purpose and by making the necessary circuit modification any desired number of preliminary impulses may be taken care of and an equal number of impulses erased from the regular series following such preliminary impulses. Accordingly the first register switch always takes a position which corresponds exactly to the number of impulses contained in the regular series intended to set such switch regardless of whether or not the regular series is preceded by preliminary impulses. 100

By this arrangement, the first position of the register switch 140 is reserved to take care of preliminary impulses. For this reason, it is necessary to avoid the use of the ordinal 1 or any other character involving the transmission of a single impulse, as the first digit of the designation. It will be apparent that by reserving the first two or more positions of switch 140 for that purpose and by making the necessary circuit modification any desired number of preliminary impulses may be taken care of and an equal number of impulses erased from the regular series following such preliminary impulses. Accordingly the first register switch always takes a position which corresponds exactly to the number of impulses contained in the regular series intended to set such switch regardless of whether or not the regular series is preceded by preliminary impulses. 110

What is claimed is:

1. In combination, a switch having a plurality of settings, means for transmitting 120

- current impulses, means operated in response to the transmission of an impulse to move said switch to its first setting, and means responsive to a succeeding series of impulses 5 for continuing the movement of said switch to take a setting corresponding to the number of impulses contained in said succeeding series.
2. In combination, a switch having a plurality of positions, means for transmitting current impulses, means operated in response to an impulse to move said switch to a position from normal corresponding to the impulse sent, and means responsive to a succeeding series of impulses for continuing the movement of said switch to a position from normal corresponding to the number of impulses contained in said series. 10
3. In combination, a switch having a plurality of positions, means for transmitting current impulses, means responsive to a single impulse for moving said switch to its first position, and means responsive to a succeeding series of impulses for continuing 15 the movement of said switch to a position corresponding to the number of impulses in said succeeding series.
4. In combination, a step-by-step switch having a plurality of positions, means for transmitting current impulses, means responsive to an impulse for stepping said switch to a position corresponding to said impulse, and means responsive to a succeeding series of impulses for continuing the stepping movement of said switch to a position corresponding to the number of impulses in said succeeding series. 20
5. In combination, a switch having a plurality of positions, an impulse circuit and means for sending impulses over said circuit, means responsive to a single impulse in said circuit for moving said switch to its first position, a relay and means for operating the same when the switch is moved to said position, and means controlled by said relay for continuing the movement of said switch in response to a succeeding series of impulses to a position corresponding to the number 25 of impulses in said series.
6. In combination, a subscriber's line, a switch having a plurality of positions, means for associating said switch with the subscriber's line, means for sending impulses over the subscriber's line, means responsive to a single impulse for moving said switch to its first position, and means responsive to a succeeding series of impulses for continuing the movement of said switch to a position corresponding to the number of impulses contained in said succeeding series. 30
7. In combination, a switch having a plurality of positions, means for sending current impulses, means responsive to a particular impulse for moving said switch to a position corresponding to said impulse, and means operable when a succeeding series of impulses are sent to render ineffective a part of the impulses of said succeeding series and to move said switch in response to the remaining impulses of said series to a position corresponding to the total number of impulses in the series. 35
8. In combination, a switch having a plurality of settings, means for sending current impulses, means responsive to a particular impulse for giving said switch its first setting, and means operable when a succeeding series of impulses are sent to render ineffective a part of said succeeding impulses and to give said switch in response to the remaining impulses of said series a setting corresponding to the total number of impulses in the succeeding series. 40
9. In combination, a switch having a plurality of positions, means for sending current impulses, means responsive to the transmission of a single impulse for moving said switch to its corresponding position, and means operable when a succeeding series of impulses are sent to render ineffective the first impulse of said succeeding series and to continue the movement of said switch in response to the remaining impulses of the series to a position corresponding to the total number of impulses in the succeeding series. 45

In witness whereof, I hereunto subscribe my name this seventh day of September, A. D. 1920.

OTTMAR H. KOPP.
